UNITED STATES PATENT OFFICE.

JOHN HARRIS, OF CLEVELAND, OHIO, ASSIGNOR TO HARRIS MANUFACTURING COMPANY, OF CLEVELAND, OHIO, A CORPORATION OF OHIO.

ACETYLENE-GAS GENERATOR.

SPECIFICATION forming part of Letters Patent No. 694,916, dated March 4, 1902.

Application filed June 25, 1900. Serial No. 21,523. (No model.)

To all whom it may concern:

Be it known that I, JOHN HARRIS, a citizen of the United States, residing at Cleveland, in the county of Cuyahoga and State of Ohio, have invented a new and useful Acetylene-Gas Generator, of which the following is a specification.

My invention is an improved acetylene-gas generator.

One object of my invention is to provide improved means for automatically feeding water to the carbid as the gas is generated and consumed and to cut off the supply of water to the carbid when the gas is not being consumed, hence causing the apparatus to discontinue the generation of the gas.

A further object of my invention is to provide a novel form of carbid vessel in which the carbid is divided into separate charges, which are successively attacked by the water fed automatically thereto and in which the supply of water to a charge is prevented until the preceding charge has been expended.

A further object of my invention is to provide means for collecting the water of condensation from the gas as the same passes to the service-pipe.

My invention consists in the peculiar construction and combination of devices herein-after fully set forth, and pointed out in the claims.

In the accompanying drawings, Figure 1 is a vertical sectional view of an acetylene-gas-generating apparatus embodying my improvements. Fig. 2 is a transverse sectional view of the same, taken on the line 2 2 of Fig. 1. Fig. 3 is a detail perspective view of the feed-water cock and the vertically-movable rod carried by the gas-bell to automatically operate the cock and control the supply of water to the carbid. Fig. 4 is a detail perspective view of the carbid vessel. Fig. 5 is a detail sectional view of the feed-water cock.

The water-tank 1 is provided with a false bottom 2 and is formed with a water-chamber 3 in its lower side. A vertically-disposed standard 4, which is here shown as a pipe, is secured to and extends through central openings in the bottom of the water-tank and in the false bottom 2 thereof by means of nuts 5. The gas-bell 6 is provided with a cen-

trally-disposed depending tube 7, which slides on the standard 4, said standard and said tube 7 coacting to form guides to center the bell in the water-tank. In the water-chamber 3, below tank 1, is a seal-chamber 8, from the upper end of which extends a gas-inlet pipe 9, the upper end of which is in the gas-space of the bell. The gas-exit pipe 10 is also located in the water-tank, the upper end of which communicates with the gas-space of the bell and the lower end of which is open and submerged in the water in the chamber 3. A coupling 11, which leads from one side of the pipe 10, near the lower end thereof, is adapted for the attachment of the service-pipe. A pipe 12 depends from the upper side of the gas-bell and telescopes loosely on a blow-off pipe 13 and is provided with an opening 14, which when the same is uncovered by the rising of the bell to an abnormal extent permits the excess gas to be discharged through pipes 12 13 to the air outside of the house.

On one side of the water-tank is located the generating vessel 15, which is provided with a cover 16 and means for firmly securing the cover in place, so that no gas can escape from the generating-chamber into the air. A pipe 17 leads from the center of the gas-generating chamber to the seal vessel 8 in the water-chamber 3, and the downturned inner end of said pipe 17 is submerged and sealed in the water within the seal-chamber 8.

On one side of the water-tank 1 is a water-supply tank 18. A feed-water pipe 19 leads from the bottom of said water-supply tank to a point within the gas-generating chamber, where it is provided with a suitable discharge-nozzle 20, and in the said feed-water pipe is a cock 21, having contracted openings 22, between which is located the hollow turning plug 23, which is provided at one end with a radial arm 24, which is bifurcated to form an open slot 25.

A bracket-arm 26 projects from the gas-bell, and to the same is attached the upper end of a vertically-disposed operating-rod 27. The lower portion of the said rod operates in a tubular guide 28, which is secured to one side of the water-tank 1, and the said operating-rod has a vertical slot 29, appropriately

located, through which slot the arm 24 extends, and the open slot 25 of said arm is engaged by a transversely-disposed pin 30 in the operating-rod, as shown in Fig. 3. From 5 the foregoing description and by reference to the drawings it will be understood that as the bell rises and descends the plug 23 is turned automatically, and hence controls the supply of water to the gas-generating chamber, the 10 water-supply being cut off automatically when the bell ascends and reestablished upon the descent of the bell, and hence the generation of the gas is automatically controlled, the gas is generated only when the same is 15 being used, and when the gas is not being used the consequent rise of the bell cuts off the supply of water to the generating-chamber, and the generation of gas therein is discontinued. When the bell rises to such an 20 extent as to cause the pin 30 to clear the slot 25 of arm 24 and the slot 29 of the operating-rod to clear said bifurcated arm, the water-supply is entirely cut off from the gas-generating chamber by the cock 21, and one fork 25 of the arm 24 bears against one side of said operating-rod, while the latter may continue to ascend, thereby locking the cock in a closed position, as will be understood. Upon the 30 descent of the bell and the operating-rod the arm 24 by gravity reenters the lower portion of slot 29, the pin 30 reengages the slot 25 of arm 24, and a continued descent of the bell and operating-rod causes the cock to be reopened and the supply of water to the gas-generating chamber to be renewed. 35

The pin 30 moves outward in the slot in the forked arm, and the proportions of the slot 29 and forked arm 24 are such that when the gas-bell is in its lowermost position the pin 30 continues to be engaged by the forks of 40 the arm, and hence the cock 31 is locked in its fully-opened position.

The carbid vessel 31, which is placed in the generating-chamber and is provided with 45 a bail or handle 32, whereby it may be readily removed therefrom and carried about, is circular in form, fits snugly within the generating-chamber, and is provided with a series of radial pockets 33. Each of the pockets is of 50 the capacity to contain a charge of carbid, and the partition-plates 34, which separate the said radial pockets, are cut away on their upper sides on reentrant angles, as at 35. The carbid charges in the various pockets 55 are brought successively into action as the same are attacked by the water. As the water attacks the carbid in one of the pockets the carbid during the generation of the gas thereby swells and rises above the level of the 60 lowest points of the upper edges of the partition-plates, thereby preventing the escape of the water into the next adjoining pocket until it has become entirely slaked, whereupon the water passes from the pocket containing 65 the slaked discharge of carbid into the next pocket in succession containing a charge of active carbid, and so on throughout the se-

ries, and hence the charges of carbid are successively brought into action and each charge in succession is thoroughly slaked before the water attacks the charge which is next in the series. Hence the gas-generating apparatus requires but little attention to keep the same in operation. 70

When the gas-generating apparatus is in 75 operation, the gas passes from the generating-chamber through the pipe 17 into the seal-chamber 8, which communicates with the water-chamber 3, bubbles up through the water in the seal-chamber, being thereby washed 80 and purified, passes through the pipe 9 into the bell, and passes from the bell through the pipe 10 to the service-pipe. The water which becomes condensed from the gas passes through the lower submerged end of the pipe 10 into the water-chamber 3. The water in the latter is maintained at a proper level by an overflow-pipe 36. 85

Having thus described my invention, I claim— 90

1. In an acetylene-gas generator, the combination of a feed-water pipe, a cock therein having a forked arm, and a vertically-movable rod, carried by the gas-bell and having a vertical slot to receive said forked arm and 95 a pin to engage said forked arm, substantially as described. 95

2. In an acetylene-gas apparatus, a gasometer or holder, a gas-generator adjacent to said holder, pipes connecting said generator with 100 said holder, a water-supply pipe leading to said generator and provided with a valve, a bar secured vertically to the drum or cover of the holder and movable vertically therewith, and provided with vertical slots, and a 105 fork connected with the stem of said valve, the prongs or arms of which are adapted to slide in said slots in said bar and to be locked against downward movement thereby when said bar is elevated, substantially as shown 110 and described. 110

3. In an acetylene-gas apparatus, a water-tank, a gas-holder placed in said tank, and comprising a vertically-movable drum or cover, a generator adjacent to said holder, 115 pipes leading from said generator to said holder, a water-supply pipe leading to said generator, and provided with a valve, a bar secured vertically to the holder and movable vertically therewith, and provided with vertical slots, and a fork connected with the stem of said valve, the prongs or arms of which are adapted to move in said slots during the movement of the holder, whereby said fork and valve are locked when said holder is in 125 its lowest position, substantially as shown and described. 120

4. In an acetylene-gas apparatus, a water-tank, a vertically-movable drum or holder placed therein, a generator connected with 130 said tank and in communication with said holder, a water-supply pipe connected with said generator, and provided with a valve, a vertical bar secured to the holder, and verti-

cally movable therewith, and a fork connected with the stem of said valve, the arms or prongs of which are adapted to slide in slots in said bar and be locked thereby against movement when said bar is elevated or depressed, substantially as described.

5. In an acetylene-gas apparatus, a water-tank, a vertically-movable holder placed therein, a generator adjacent to said holder and in communication therewith, a supplemental water-tank supported above said first-named tank, a pipe leading therefrom to said generator, and provided with a valve, a fork connected with the stem of said valve, a ver-

tical bar connected with the holder and movable vertically therewith, and provided with a guide for the arms or prongs of said fork, and a slot or slots into which the prongs or arms of said fork project during the movement of said bar, substantially as shown and described.

In testimony that I claim the foregoing as my own I have hereto affixed my signature in the presence of two witnesses.

JOHN HARRIS.
